Primary Examiner—Caron D. Veynar*Attorney, Agent, or Firm*—Taylor J. Ross[57] **CLAIM**

The ornamental design for a cutlery handle, as shown and described.

DESCRIPTION

FIG. 1 is a top and side perspective view of a cutlery handle showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The knife blade shown in phantom lines is for environmental purposes only and forms no part of the claimed design.
